LOCKING MEANS FOR OIL BARRELS

Peter Thorpe Doubble, Ladysmith, British Columbia, Canada

Application December 4, 1945, Serial No. 632,634

1 Claim. (Cl. 220—85)

1

My invention relates to improvements in locking means for oil barrels.

For the lack of satisfactory locking means for steel drums or barrels in which oil and gasoline is carried, many logging and mining operators and civil engineering contractors lose substantial sums of money through the pilfering of or otherwise unauthorized use of gasoline and oil. Large quantities of oil are stored temporarily in steel drums by such operators as above enumerated because the nature of their work makes the installation of underground tanks impracticable and the present invention is designed to safeguard the contents of the barrels whether they are stored in sheds or in the open. Other objects are to provide a means for automatically opening the vent to the barrel incidental to the removal of the locking means, and for locking the normal outlet from the barrel and closing the barrel vent simultaneously.

Referring to the drawings:

Fig. 1 is a general view, part in section, of the invention.

Fig. 2 is a detail view of the vent in open position.

In the drawings like characters of reference indicate corresponding parts in each figure.

The numeral 1 indicates generally an oil drum having an outlet flange 2 and a vent flange 3 in the upper end wall 4. A valve fitting 6 is adapted to be screwed into the outlet flange 2. This fitting terminates at its base in a nipple 7 having a large thread 8 and a small thread 9 so as to be capable of fitting any normal oil drum outlet flange. The nipple is provided with a nut 11 which carries a cylindrical base 12 and a broad vertical column 13 having a round aperture 14 at its upper end.

An outlet valve 16 is fitted into the base 12 and communicates with the interior of the barrel 1, the valve is preferably of the push button spring loaded type, which is self closing, as shown in Figure 1, and is adapted to be covered with a cylindrical cap 17 which fits snugly onto the cylindrical base and is adapted to be held in place thereon by a bar 19 extending through opposing apertures 20 formed in the cap adjacent its upper end.

A vent fitting 21 is adapted for insertion into the flange 3 and consists of a cylindrical body 22 having a nut 23 and a large and a small diameter thread generally indicated by the numerals 24 and 25. The body is provided with a central bore 27 which communicates with the barrel and with a valve recess 28 in the upper end of the body. Communicating with the valve recess and the

2

bore 27 is a transverse passage 30 extending to the outside of the body. An opening 31 extends through the body above the base of the recess which is tapered inwardly from opposite sides as at 32 and is adapted to receive the headed end 34 of the bar 19. A rubber valve 35 is fitted in the recess 28 which is substantially semi-spherical as at 36 in its upper portion and terminates in a cone 37 at its base. The cone 37 is of lesser diameter than the valve recess 28 and the upper portion 36 rests upon an annular rim 38 to support the apex of the cone 37 out of contact with the bore 27, see Figure 2, but when the bar 19 is inserted into the opening 31 the semi-spherical portion 36 of the valve 35 is depressed and the cone is driven downwards to close off the bore 27. When the bar is removed, the valve will resume its normal shape, leaving the vent open as shown in Figure 2.

20 When a drum is received, the bungs are removed from the flanges 2 and 3 and a fitting 6 is screwed into the flange 2 and a vent fitting 21 is screwed into the flange 3. The bar 19 can be used if desired to tighten up these fittings into their flanges or an appropriate wrench used instead. When some of the contents are to be withdrawn from the drum it is appropriately tilted and the contents are withdrawn through the valve 16 in the usual way. Since the rubber valve 35 in the vent fitting is not under axial pressure from the bar, the vent bore 27 will be open so that free drawing can be obtained. When it is desired to lock the drum, the cap 17 is placed upon the valve fitting 6 and the openings 20 aligned with the aperture 14 of the column 13. The bar 19 is inserted through the opening 31, thus depressing the rubber valve 35 to close the vent and then passed through the cap 17 and the column 13 and a padlock 39 secured to its eyed end as at 40, thus preventing any access to the valve 16 and leaving the vent closed, so that nothing can be withdrawn from the drum even through the vent bore 27.

What I claim as my invention is:

45 A locking means for oil drums and the like having a threaded outlet opening and a threaded vent opening, a plug adapted for insertion into the outlet opening, a vent plug adapted for insertion into the vent opening, each of said plugs having a transverse opening, a bar adapted for insertion through the openings, means for locking the bar against removal from the openings, said vent plug having a vent passage adapted to communicate with the interior of the drum and a 50 valve adapted to close the vent passage in re-

sponse to the insertion of the bar into the opening in the vent plug.
